UNITED STATES PATENT OFFICE

TIMOTHY L. PFLUEGER, OF SAN FRANCISCO, CALIFORNIA, ASSIGNOR TO STANDARD STATIONS, INC., OF SAN FRANCISCO, CALIFORNIA, A CORPORATION OF DELAWARE

DESIGN FOR A BUILDING

Application filed February 15, 1932. Serial No. 42,870. Term of patent 14 years.

To all whom it may concern:

Be it known that I, TIMOTHY L. PFLUEGER, a citizen of the United States of America, residing in the city and county of San Francisco, State of California, have invented a new, original, and ornamental Design for a Building, of which the following is a specification, reference being had to the accompanying drawing, forming part thereof.

Figure 1 is a front perspective view of a

building and Figure 2 is a top plan view showing my new design.

I claim:

The ornamental design for a building, as shown.

Signed at San Francisco, California, the 9th day of February, 1932.

TIMOTHY L. PFLUEGER.
